UNITED STATES PATENT OFFICE.

FREDERICK W. KOPP AND WILLIAM RUNNING, OF CLEVELAND, OHIO.

WATCH.

1,117,196.

Specification of Letters Patent.

Patented Nov. 17, 1914.

Application filed June 18, 1913. Serial No. 774,357.

To all whom it may concern:

Be it known that we, FREDERICK W. KOPP, subject of the Czar of Russia, and WILLIAM RUNNING, citizen of the United States, residing at Cleveland, in the county of Cuyahoga and State of Ohio, have invented a new and useful Improvement in Watches, of which the following is a specification, the principle of the invention being herein explained and the best mode in which we have contemplated applying that principle, so as to distinguish it from other inventions.

Our invention has general reference to a watch construction and more especially to improvements upon certain component parts thereof.

One object has been the provision of a balance-wheel cock of such configuration that it will insure conjunctive advantages in its relation to other parts which it adjoins.

Another object has been the reduction in the number of certain primary parts, the rearrangement of others whereby a larger proportion of space within a given case may be utilized for those parts which are universally essential as well as what few we have seen fit to add thereto.

A final object is the provision of a watch movement which necessitates few even slight changes of individual parts and hence is sufficiently simple and economical of manufacture, which is adapted for both hunting and open-face cases, lever or pendant-set and which permits of reduction to lady-sized cases and their requisite delicate workmanship.

As is thoroughly appreciated by all jewelers, the insertion or removal of balance wheel cocks is rather a delicate procedure owing to the attendant likelihood of fracturing the pivot of the balance staff. Such balance wheel bridges or cocks must in almost all instances be removed prior to an inspection or repair of other parts disposed beneath the plane thereof and consequently the removal of this particular member is very frequently required. Our particular balance wheel cock as shown in the drawing is not only of the maximum thickness so as to extend deep into the case and abut the plate below but is provided as well with an elongated curved extension constituting an arc of a circle and approaching near its extremity the direction of projection of the balance bridge portion proper. Our style of bridge furthermore has two edge sur-

faces transverse with respect to the annular rim of the case and these are adapted to form a close mechanical fit with other complementary bridge members which are likewise of maximum thickness. It will be seen, therefore, that in order to affect the removal of a balance wheel cock embodying our invention it becomes necessary to lift it straight out, that is in a direction perpendicular with the plane of the case, the extension serving in the meantime as a guide in contact with the inner surface of the latter. It is this restraint in the manner of insertion or removal which is adapted to preclude lateral strain upon the pivot of or injury to the balance staff. When the entire movement is withdrawn from the case, preparatory to examination, the arcuate extension effectually serves to protect the balance wheel from the repairer's fingers.

The supporting structure or frame constituting as assembled the circular body of the mechanism which is to be lifted into the particular sized case (#16 or smaller); comprises only three bridge members and these are complementary of each other. Each of these three supporting or bridge members is provided with an arcuate rim and the extent of the respective rims is unequal. The balance-wheel cock explained in the previous paragraph is one of these three bridge members. The other two, hereinafter styled "barrel" and "train" bridges, abut the transverse end surfaces of the balance wheel cock throughout their entire depth or thickness whereas they do not themselves abut. The formation of the outer surfaces of the arcuate rims of these three bridge members is such that they obviate the necessity for a special dust band. Incidentally a simpler and more rigid and tight fit therebetween is assured.

The inventive conception is embodied in means which are hereinafter explained and variously combined in the claims, while the annexed drawing and particular description thereof together set forth in detail one specific means constituting our invention, the disclosed means however, being but one of various mechanical forms in which the principle of our invention may be applied.

In the annexed drawing:—Figure I. is a plan view on double scale, of a watch embodying our invention with the back cover of the case removed. Fig. II. is a similar view showing three additional members re-

5 moved. Fig. III. is an end view of Fig. II. with the case removed, another part cut away, and looking to the right. Fig. IV. is an end view of Fig. I. with the case removed and looking in the same direction. Fig. V. is a view of Fig. II. with the case removed and looking upwardly.

10 The construction comprises in this instance a standard circular open-face case A, having a stem a^1 and a ring a^2 secured thereto. The winding bar, winding pinion, crown wheel and ratchet click, while essential, need not be shown here. The case A is provided, as is customary, with an interiorly 15 projecting annular flange (not seen) against which the interior mechanism proper is adapted to be seated. The usual pillar plate B of circular form precisely fits and overlies this flange. The pillar plate B is provided with a central opening and supports 20 on its outer face the dial. The three bridge members have complementarily arcuate outer rims forming together a peripheral surface slightly smaller than the peripheral 25 surface of the plate B, and are intended to be secured not only to the latter but relative to the case A. This fastening with respect to the case is affected through the medium of two nearly oppositely disposed 30 case-screws a^3 and a^4 . The thickness of the balance-wheel and train bridges which I have designated respectively as D and E, is the same, and such that in addition to the thickness of the pillar plate B the whole 35 may lie within the planes of the front and back surface of the case A. The barrel bridge C is somewhat less thick.

40 The bridge C is of the largest arcuate extent as will be apparent from an inspection of Fig. II., and since of slightly reduced thickness is somewhat depressed with respect to the other two bridges when disposed in similar manner contiguous to the plate B. A top or cover plate which I have designated 45 with the reference character F has an arcuate edge corresponding with the arcuate edge of the barrel bridge C, and is of a thickness such that when superimposed upon the latter it will lie flush with the upper 50 surface of the bridges D and E. The barrel-bridge C and cover plate F are each provided with three registering steady-pin holes c^1 and f^1 respectively, through which securing-screws f^2 are adapted to extend as shown in 55 Fig. I. The bridge C and plate F are provided at one corresponding end with aligned side edge surfaces c^2 and f^2 .

60 The cock D as already stated is in fact a balance wheel bridge secured to the pillar plate B by means of a screw d^1 , and comprises an inwardly projecting bridge portion proper d^2 , arcuate extension d^3 , and side edge surfaces d^4 and d^5 . The line of projection of the edge surface d^5 corresponds 65 with and abuts as a close mechanical fit the

two edge surfaces c^2 and f^2 . Passing through a suitable opening near the extremity of the balance wheel bridge proper d^2 is a balance staff d^6 . This staff supports a hair-spring and balance wheel combination d^7 . A regulatory "fast" and "slow" device designated entire as d^8 is shown disposed upon the upper surface of the balance wheel bridge and since long in vogue requires no specific description. 75

The bridge E, while having its actuate rim of the maximum thickness earlier explained has its upper surface depressed or cut away to form a plurality of peep spaces as seen in Figs. I, II and V. One side edge e^1 of the member E being of maximum thickness abuts the edge d^4 as clearly seen in Figs. I, IV and V. The peep spaces of the member E are three in number and extend from the inner surface of its rim inwardly in the general direction of the balance wheel bridge D. They are in fact elongated slots to form three ancillary bridges e^2 , e^3 , and e^4 . The support E is secured to the pillar plate B by four screws each designated as e^5 . One of these screws passes through each of the subsidiary bridges e^2 , e^3 and e^4 whereas the fourth secures that end of the train bridge E nearest the edge e^1 . Each of the subsidiary bridges has a shaft 95 mounted upon its inner extremity so as to extend between it and the plate B. These shafts are designated respectively e^6 , e^7 and e^8 , and their purpose even though anticipated will hereinafter more clearly appear. 100

A main-spring arbor G, suitably jeweled, is supported in an upright position between plates B and F and nearest the barrel bridge C. A main-spring barrel g^1 of any approved form is mounted upon the arbor G and fixed upon the latter is a winding wheel having gear teeth g^2 . Operatively connected to the barrel g^1 and to the arbor is the main-spring, which should be heavier, that is thicker in proportion to its usual length. Inasmuch as nothing new is claimed for the mode of securing such main-spring, it is not required that it be here shown. A shaft H is similarly supported as the arbor G and some distance from it. This shaft carries the pinion h^1 adapted to mesh with the teeth g^2 , and lying above the pinion h^1 is a gear wheel h^2 having gear teeth h^3 . Still another shaft J is similarly supported beyond the shaft H and somewhat nearer the balance wheel bridge D. This shaft supports the pinion j^1 adapted to lie in mesh with the gear h^2 , while underneath this pinion j^1 is a gear wheel j^2 having teeth j^3 . The usual center wheel shaft K is mounted in the center of the case and likewise supports a pinion k^1 which is in mesh with the gear j^2 . Above the pinion k^1 is the center wheel itself k^2 having peripheral teeth k^3 . The opposite extremity of the shaft K, has mounted ex- 120 125 130

teriorly of the dial the hour hand h^4 and minute hand h^5 whose connection through the medium of center and cannon pinions respectively it is not necessary to explain, 5 since universally employed in order to effect the proper rotational relationship therebetween.

As will now be apparent from what has gone before, the gears h^2 and j^2 comprise the intermediary connection between the main-spring barrel and center wheel of our watch and as constructed with regard to the tension of the main-spring are calculated to make possible the continuous rotation of the 10 center wheel for a period of eight days or more. The speed of rotation of the center wheel is controlled by the customary train of limiting mechanism to be now described. The shaft e^6 supports what is known as the 15 "third" gear wheel L and a pinion l^7 shown dotted, in Fig. II. as being in mesh with the teeth h^3 on the center wheel. The shaft e^7 similarly supports the "fourth" or what is 20 in reality the second-hand wheel M and also in dotted lines a pinion adjacent thereto which is logically implied as in mesh with gear L. So also the shaft e^8 supports the 25 escapement wheel N of usual construction and adjacent to it a smaller pinion likewise dotted and in mesh with the second-hand 30 wheel M.

Fig. I. clearly depicts a forked lever O. This lever is operatively connected to articulate with the balance-wheel staff d^6 and at 35 its opposite end with the usual impulse and locking pallets adapted to successively release and arrest the escape wheel N.

As will now be readily understood by all sufficiently conversant with the art, the gear 40 wheels L and M together with the escapement wheel N and lever O connecting the latter with the balance wheel d^7 constitute the limiting train or escapement mechanism which ultimately prescribes the speed of 45 rotation of the minute and hour hands.

The operation of the watch which has been described is as follows: It being assumed that the main-spring, whose outer end is attached to the spring barrel and whose inner 50 end is made fast either to the barrel arbor or the hub of the winding wheel, has been wound; and winding wheel which is fixed to the barrel arbor caused to turn in consequence; the other parts will be successively 55 actuated in this wise. The winding wheel g^2 indirectly rotates the gear h^2 through the medium of pinion h^1 which in turn rotates indirectly through the medium of another pinion j^1 the gear wheel j^2 , and this last 60 mentioned gear wheel meshes with the center pinion to tend to rotate it and hence the center wheel. This center wheel is controlled however, by the restraining or limiting train so called which train comprises a 65 "third wheel" L whose pinion is in mesh

with the center wheel h^2 , also a "fourth" wheel or as it happens the "second-hand" wheel the escapement wheel N with its pinion, the forked lever O and finally the balance wheel d^7 with its regulatory mechanism. The tendency of the wheels L and N is, of course, to turn the escapement wheel. This latter is hindered, however, by the successive swings of the pallet jewels in their engagement with the escape teeth thereon. 70 The swinging of the forked lever operates to turn the balance staff and deflect the hair-spring connected therewith. This latter on reacting carries the balance wheel in the opposite direction. The frequency of the 75 balance vibrations is thereafter determined by the resistance which the hair-spring is made to offer.

It should be appreciated that the disposition of the various parts of our watch mechanism is such as to utilize more completely the space available between the planes of opposite sides of a standard watch case; as to leave open to inspection but slightly less than half of the area encompassed by the 80 case; and as to inclose and hence protect, when lifted from the case, certain of the more delicate parts. These desired results are brought about in a measure by the nicety of fit between the balance-wheel and other 85 bridges.

Our invention being thus described with sufficient thoroughness, what we desire to secure by Letters Patent and therefore claim specifically, is:

1. A watch comprising the combination of a watch-case, plates adjacent opposite sides thereof, a plurality of members forming together a major portion of an annular rim, and a balance-wheel bridge contiguous 100 each of said plates and forming the complementary portion of such rim, said bridge having edge surfaces transverse with respect to the plane of said case and extending inwardly from its own rim, different of said 105 members having corresponding edge surfaces adapted to coincide with the edge surfaces of said bridge respectively, for the useful purpose specified.

2. A watch comprising the combination of a plurality of bridges forming together a portion of an annular rim, one of said bridges having an end surface extending inwardly from its own rim portion, said surface being transverse with respect to the 115 plane of the watch, a balance-wheel bridge interposed between said other bridges and having a side surface conforming to and abutting said first mentioned surface, said balance-wheel bridge furthermore fashioned 120 with an arcuate surface forming the complementary portion of said annular rim.

3. A watch comprising the combination with a case, of a plurality of members forming together a portion of an annular rim 125

- conforming to and abutting the inner rim of said case, of a balance-wheel bridge disposed in the same plane as and forming another portion of such rim, one of said members and bridge having adjacent edges projecting inwardly a considerable distance and contiguous, whereby said bridge may be withdrawn without injury to its staff.
4. A watch comprising the combination of a plurality of bridges forming together the major portion of an annular rim, a balance-wheel bridge interposed between and having one part projecting toward such major rim portion and contiguous with a similarly projecting edge of one of said first mentioned bridges, said balance-wheel bridge furthermore provided with an elongated arcuate extension forming another portion of said rim and having an edge surface contiguous with the proximate edge surface of another of said first mentioned bridges, whereby said balance-wheel bridge must be withdrawn in the direction of projection of its staff.
5. A watch comprising the combination with a watch-case having a dial plate, of a bridge member contiguous to said plate, a balance-wheel bridge contiguous to said plate, said balance-wheel bridge having an arcuate rim of maximum thickness with respect to the depth of said watch-case, said bridge member and balance-wheel bridge having adjacent edge surfaces transverse with respect to the plane of said plate extending inwardly relative to said rims and adapted to abut as a close mechanical fit, whereby the balance-wheel bridge may be withdrawn without injury to the balance staff.
6. A watch comprising the combination with a plurality of members forming together a portion of an annular rim, of a balance-wheel bridge disposed in the same plane as and forming another portion of such rim, said balance-wheel bridge having transverse edge surfaces extending inwardly in different directions from such rim, a pair of said members having corresponding edge surfaces adapted to abut the aforementioned surfaces respectively, whereby the plane of the balance-wheel bridge is held parallel to the plane of the case while being withdrawn for the useful purpose specified.
7. A watch comprising the combination with a watch case having a dial plate, of a plurality of bridge members contiguous said plate, said members having complementary arcuate rim surfaces transverse with respect to the plane of said plate, one of said members having a pair of edge surfaces correspondingly transverse and extending at an angle relatively to each other, a distinct pair of said members each having an edge surface transverse with respect to the plane of said plate and coinciding with one of said first mentioned surfaces respectively, said coinciding surfaces being adapted to abut inwardly beyond said rims, whereby the balance-wheel bridge is necessarily withdrawn without injury to the balance staff thereof.
8. A watch comprising the combination of a watch case having a pillar plate, a bridge member contiguous to said plate and having an elongated side edge surface transverse with respect to the plane of said plate, a cover plate for such bridge member having a corresponding side edge in the same transverse plane as said first mentioned side edge, and a balance cock contiguous to said pillar plate and flush with the said cover plate, said cock having an arcuate extension conforming to the rim of said case and also having a side edge corresponding to and abutting said combined edges, whereby said cock must be withdrawn transversely to the plane of the case for the full extent of its staff for the useful purpose specified.

Signed by us, this 16th day of June, 1913.
FREDERICK W. KOPP.
WILLIAM RUNNING.
